(57) CLAIM

I claim the ornamental design for a microphone, as shown and described.

DESCRIPTION

FIG. 1 is a perspective view of a microphone showing my new design, which is also a mirror image of the opposite perspective view thereof;

FIG. 2 is a bottom view thereof;

FIG. 3 is a top view thereof;

FIG. 4 is a front view thereof which is a mirror image of the opposite side thereof;

FIG. 5 is a right side view thereof which is also a mirror image of the opposite side thereof;

FIG. 6 is a perspective view of a first alternate embodiment of my new design, which is also a mirror image of the opposite perspective view thereof;

FIG. 7 is a bottom view thereof;

FIG. 8 is a top view thereof;

FIG. 9 is a front view thereof which is also a mirror image of the opposite side view thereof; and,

FIG. 10 is a right side view thereof which is a mirror image of the opposite side view thereof.
